UNITED STATES PATENT OFFICE

163,704

LADY'S STOCKING

Joseph Mann, Brookline, Mass.

Application June 2, 1950, Serial No. 10,318

Term of patent 3½ years

(Cl. D47—7)

To all whom it may concern:

Be it known that I, Joseph Mann, a citizen of the United States of America, residing at Brookline, in the county of Norfolk and Commonwealth of Massachusetts, have invented a new, original, and ornamental Design for a Lady's Stocking, of which the following is a specification, reference being had to the accompanying drawing, forming part thereof.

Fig. 1 is a fragmentary rear elevation of a lady's stocking showing my new design; and

Fig. 2 is a side perspective of a lady's stocking showing the design illustrated in Fig. 1.

I claim:

The ornamental design for a lady's stocking, as shown.

JOSEPH MANN.
